COLUMBIA PLANOGRAPH CO., WASHINGTON, D. C.

UNITED STATES PATENT OFFICE.

JOHN C. DUNTON, OF GRAND RAPIDS, MICHIGAN.

WOODWORKING-MACHINE.

1,159,909.

Specification of Letters Patent.

Patented Nov. 9, 1915.

Application filed April 22, 1914. Serial No. 833,605.

To all whom it may concern:

Be it known that I, JOHN C. DUNTON, a citizen of the United States, residing at Grand Rapids, in the county of Kent and State of Michigan, have invented certain new and useful Improvements in Woodworking-Machines, of which the following is a specification.

This invention relates to improvements in 10 woodworking machines.

The objects of this invention are:

First, to provide an improved machine of 15 this type in which the tonguing and grooving operation is completed at one movement of the machine. Second, to provide an improved woodworking machine, having improved adjusting means for squaring up the work. Third, to provide in a machine of this type, an improved clamp to hold the 20 block of wood to be operated upon.

Further objects, and objects relating to details and economies of structure and operations will definitely appear from the detailed description to follow.

25 I accomplish the objects of my invention by the devices and means described in the following specification.

The invention is clearly defined and pointed out in the claims.

30 A structure constituting a preferred embodiment of my invention is clearly illustrated in the accompanying drawings forming a part of this specification, in which:

Figure I is a top plan view of a structure 35 embodying my invention. Fig. II is an enlarged sectional view taken on the irregular line 2—2 of Fig. I. Fig. III is an enlarged sectional view taken on the line 3—3 of Fig. I, showing in detail the tapered pin for adjusting the trough relative to the work table. Fig. IV is an enlarged detail sectional view on the line 4—4 of Fig. I, showing in detail the means for squaring the block of 40 wood in the clamp. Fig. V is an enlarged 45 sectional view on the line 5—5 of Fig. I. Fig. VI is a perspective view of the clamping plate removed from the device. Fig. VII is a bottom plan view of the clamp showing the ball cages for holding the ball 50 bearings. Fig. VIII is an enlarged sectional view on the line 8—8 of Fig. VI, showing in detail one of the studs on the bottom of the clamping plate. Fig. IX is 55 an enlarged sectional view on the line 9—9 of Fig. I, a part thereof being broken away, showing in detail two of the springs for re-

turning the clamping plate to its normal position. Fig. X is a detail perspective view of the end of the claw member engaging the block of wood. Fig. XI is an enlarged sectional view on the line 11—11 of Fig. I, showing in detail the tonguing and grooving cutter heads.

In the drawing, similar reference characters refer to similar parts throughout the 65 several views and the sectional views are taken looking in the direction of the little arrows at the ends of the section lines.

Considering the numbered parts of the 70 drawing, 1 is the work table to which is secured the trough 2. Both ends of the trough are provided with ears 3 through which pass the bolts 4 engaging in the slotted ways 5—5 provided in the work table 1. By this means, the trough 2 is 75 adjustably secured to the face of the work table. At the ends, the work table is provided with a plurality of tapered openings 6, 6, in which a tapered pin 7 is adapted to seat, the tapered pin passing through a suitable opening 8 provided in the trough 2. By this means a very delicate adjustment of 80 the trough laterally is secured, by means of which the trough is secured with its edges parallel to the edges of the table and at 85 varying distances therefrom depending upon the size of the block to be operated upon.

About midway of the work table, is provided a spindle 9 passing through said table 90 and carrying thereon the grooving cutter head 10. The grooving cutter head 10 is provided with an annular cutting edge 12. Beneath this cutter is a circular disk slightly larger in circumference than the cutter, both 95 this and the cutter resting on a shoulder on said spindle. Between the disk and cutter may be placed spacing disks which vary the distance of the groove from either the top or bottom of the block of wood. It is usually desirable to have the groove come exactly midway and by this means the distance may be varied according to the thickness of the disks employed. In line with said grooving cutter head and on the opposite side of 100 the trough therefrom, is provided a tonguing cutter head 14 which is similarly mounted on a bolt 15 and spaced from the work table by means of the sleeve 16. This tonguing cutter head, instead of being mounted in a 105 fixed position, as is the grooving cutter head, has the spindle 15 passing through a slot 18

provided in the work table, so that the distance of the tonguing cutter head from the trough may be regulated by moving the spindle 15 back and forth in the slot 18. By 5 means of this adjustment, and the adjustment of the trough relative to the work table, the machine may be changed so as to accommodate blocks of wood of different widths.

10 The principal feature of my machine resides in the device for clamping the blocks of wood to be tongued and grooved and for carrying them past the cutter heads. The clamp comprises a base plate 19 provided with corner posts 20, 20. The top plate 21 is secured to the corner posts by means of the bolts 22, 22 and consists of a pair of side members provided with ribs 23, 23, running longitudinally thereof, which add to the 15 strength of the structure. These ribs are connected by means of a pair of cross pieces 24, 24.

25 is the clamping plate which is provided with the cut away portions 26, 26, at each end thereof. The bottom of the clamping plate is provided with a plurality of studs 27 which are fixed in the lower face of the clamping plate and project so as to bite into the block of wood held in the clamp. 30 The clamping plate 25 is supported by means of headed pins 28 and 29, threaded into said clamping plate, extending upwardly therefrom and passing through suitable perforations in the top plate 21. For each of these 35 pins, springs, such as 30 and 31 are provided, said springs being confined between the heads of the pins and the top plate 21, so that the springs tend to force the clamping plate toward the top plate. The pair of 40 springs 31, 31, which are provided on the front pins 29, 29, are stronger than the springs 30, 30, on the top pins 28, 28. The object of this will be hereinafter set forth.

45 The clamping plate is provided with a beveled groove or channel 32 opening into the rear cut away portion 26. A fork like cam member 33 is provided, having a handle 34 and pivoted on a rod 35 which is secured to the ribs 23, 23, of the top plate. The cam member 33 has cams on either branch of the fork thereof. To these cams is secured the rod 36 which carries the spring strip 37 forming a claw member having its rear end wrapped around said rod 36. The forward 50 end of said spring strip 37 is struck downwardly as at 38 and provided at its lower end with a plurality of teeth 39 which engage the block of wood 40 within the clamp. A tongue 41 is struck back from the spring 55 strip 37 near its forward end, and this tongue 41 is adapted to ride in the groove 32 so as to lift the spring strip 37 as the cam member is turned to release the block. This 60 helps to lift the claw member out of contact with the wood.

The clamping plate 25 carries near the end of the groove 32, the headed pins 42 which are threaded into the clamping plate, and pass through suitable perforations in the bar 43, which rests on top of the clamping plate above the groove 32. Compression 70 springs 44 are confined between said bar 43 and the heads of the pins 42, said springs tending to hold the bar 43 normally in engagement with the clamping plate.

75 The clamp is provided with a bar 45 extending transversely thereof at the rear end of the base plate and which is pivotally mounted on a pin 46 carried by said base plate centrally thereof. Screws 47 are 80 threaded into the corner posts 20 adjacent said bar 45 and the inner ends of said screws 47 engage the ends of the bars 45. These screws are provided with lock nuts 48 for holding them in adjusted position. By this 85 means, the bar 45 may be adjusted relative to the base plate. In front of this bar is a block 49 provided with a suitable opening therethrough through which the set screw 50 passes and engages in a screw threaded opening 51 in the bottom of the base plate. The inner edge of this block 49 engages the bar 45 and when the screw 50 is loosened, the block 49 is moved back and forth with the bar 45. The block of wood 40 is disposed to abut against this block 49 and it is trued up in the clamp by this means. At either end of the clamp a rod 52 is secured between the corner posts 20 and these rods 50 carry the links 53, which links are connected to a propelling chain or belt 54 passing over suitably mounted pulleys or sprocket wheels 55 at the ends of the table. Power is applied to this propelling chain to move the clamp back and forth longitudinally of the table. The means by which this 90 is done are immaterial, forming no part of my invention.

95 The bottom of the base plate is provided with a plurality of longitudinal grooves 56, 56, in which are disposed a plurality of balls 57, 57. Plates 58, 58, are secured to the bottom of the base plate by means of screws 59 and these plates are provided with slots 60, 60, through which the balls 57 protrude into engagement with the bottom of the trough. By this means, the clamp is supported in anti-frictional engagement with the bottom of the trough so that it will move 100 easily therein.

105 The operation of the device should be clear from the description of the parts given above. When the clamp is in operative position, the handle 34 is pulled rearwardly from the position shown in Fig. V, and in this position, the straight portions 61 of the cams are parallel to the top of the clamping plate. The block of wood which is to be tongued and grooved is inserted in the clamp 110 between the bottom plate and the clamping 115 plate. The handle 34 is then turned so as to 120 turn the cam member 33, and this turns the rod 36, which turns the spring strip 37, so as to 125 lift the block of wood 40 from the clamp. The 130 tongue 41 is then struck back, so as to ride in the groove 32, and this lifts the spring strip 37, so as to release the block of wood 40.

plate, with its rear edge adjacent the block 49. The handle 34 is then pulled up which brings the thicker portions of the cams into engagement with the top clamping plate 5 and forces the same downwardly against the action of the springs 30 and 31 into engagement with the block of wood which has been placed within the clamp. Inasmuch as the greatest force is first exerted on the front 10 portion of the clamping plate, the springs 31 at this point, are made stronger than the spring 30. As the clamping plate is pressed downwardly, the studs 27 bite into the block of wood and hold it against twisting and 15 turning. At the same time that the cam is brought into operative position, the claw member 37 provided with the teeth 39, is brought forward and pressed downwardly so that it bites into the block of wood and 20 shoves the same into abutting engagement with the block 49. The bar 43 engages this claw member and since this bar is held resiliently in position by the springs 44, after the teeth have taken hold of the block of 25 wood, the bar 43 will yield and allow the claw member to move upwardly somewhat so that the teeth will not be forced to an inordinate depth into the block of wood.

After the block of wood has been fixed in 30 the clamp, and clamped in position, the clamp is drawn the length of the table by means of the belt or chain, the base plate of the clamp riding in the trough fixed on the work table. This carries the block of wood 35 between the tonguing and grooving cutter heads 10 and 14 so that a groove is cut in one edge of the block and a tongue is cut in the other edge. The block is then removed and the clamp is returned to its original position 40 to receive another block.

In order to insure that the groove and the tongue are cut to the same depth throughout the length of the block, it is necessary that the trough extend at right angles to the line 45 drawn through the centers of these two cutter heads. This adjustment is accomplished by means of the bolts 3 engaging in the slots 5. The block of wood is abutted against the block 49 and this is adjusted relative to the 50 base plate by means of the bar 45, which can be moved back and forth by means of the bolts 47, carried by the corner posts 20.

I have shown my improved clamp and carriage in connection with tongue and 55 groove cutter heads and adapted to carry a block of wood between them. Cutter heads of other types, or saws may be used without departing from the spirit of my invention.

60 I am aware that the particular embodiment which I have here set forth is susceptible of considerable variation without departing from the spirit of my invention, and, therefore, I do not wish to be restricted 65 to the same. I have found, however, that

this particular form is to be preferred, and therefore I desire to claim the same specifically as well as broadly as indicated by the appended claims.

Having thus described my invention, what 70 I claim as new and desire to secure by Letters Patent is:

1. In a device of the class described, the combination of a table member, a channel shaped trough member adjustably secured 75 to said table member centrally thereof, a pair of cutter heads mounted on opposite sides of said trough member, one of said cutter heads being adjustable relative to the other, a clamp member adapted to engage a 80 block of wood to carry it between said cutter heads and having a base portion slidably mounted in said trough member, and means for reciprocating said clamp member, all coacting substantially as described and for 85 the purpose specified.

2. In a structure of the class described, a clamp comprising a base plate, corner posts carried by said base plate, a top plate consisting of a pair of ribbed bars secured to 90 the corner posts and connected by cross pieces, a clamping plate having its lower side provided with pointed studs disposed between said base plate and said top plate, headed pins carried by said clamping plate 95 and extending through openings in said top plate, compression springs confined between the heads of said pins and said top plate, a cam member pivotally mounted between said bars and disposed to engage said clamping plate to force it downwardly against the tension of said springs, a claw member carried by said cam member having its rear end turned downwardly and provided with teeth, said end passing through a suitable 100 opening in the clamping plate, a bar resting on the top of said clamping plate above said claw member and slidable on a pair of headed pins carried by said clamping plate, 105 springs confined between the heads of said pins and said bar and normally pressing said bar into engagement with said clamping plate, a block extending transversely of the base plate and secured thereto by means of a set screw extending centrally therethrough, 110 a bar extending transversely of the base plate behind said block and pivotally mounted on a pin centrally disposed therein, and set screws carried by the rear pair of corner posts and engaging the ends of said bar for 115 adjusting the same, all coacting substantially as described for the purpose specified.

3. In a structure of the class described, a clamp comprising a base plate, corner posts carried by said base plate, a top plate consisting of a pair of ribbed bars secured to 120 the corner posts and connected by cross pieces, a clamping plate having its lower side provided with pointed studs disposed between said base plate and said top plate, 125

130

headed pins carried by said clamping plate and extending through openings in said top plate, compression springs confined between the heads of said pins and said top plate, a 5 cam member pivotally mounted between said bars and disposed to engage said clamping plate to force it downwardly against the tension of said springs, a claw member carried by said cam member having its rear end turned downwardly and provided with teeth, said end passing through a suitable opening in the clamping plate, a bar resting on the top of said clamping plate above said claw member and slidably on a pair of headed pins carried by said clamping plate, springs confined between the heads of said pins and said bar and normally pressing said bar into engagement with said clamping plate, a bar extending transversely of the 10 base plate behind said block and pivotally mounted on a pin centrally disposed therein, and set screws carried by the rear pair of corner posts and engaging the ends of said bar for adjusting the same, all coacting substantially as described for the purpose specified.

4. In a structure of the class described, a clamp comprising a base plate, corner posts carried by said base plate, a top plate consisting of a pair of ribbed bars secured to the corner posts and connected by cross pieces, a clamping plate having its lower side provided with pointed studs to prevent twisting of the block in the carriage disposed between said base plate and said top plate, headed pins carried by said clamping plate and extending through openings in said top plate, compression springs confined between the heads of said pins and said top plate, a cam member pivotally mounted between said bars and disposed to engage said clamping plate to force it downwardly against the tension of said springs, a claw member carried by said cam member having its rear end turned downwardly and provided with teeth, said end passing through a suitable opening in the clamping plate, a bar resting on the top of said clamping plate above said claw member and slidably on a pair of headed pins carried by said clamping plate, and springs confined between the heads of said pins and said bar and normally pressing said bar into engagement with said clamping plate, all coacting substantially as described for the purpose specified.

5. In a structure of the class described, a clamp comprising a base plate, corner posts carried by said base plate, a top plate consisting of a pair of ribbed bars secured to the corner posts and connected by cross pieces, a clamping plate provided with pointed studs on its lower side disposed between said base plate and said top plate, all coacting substantially as described for the purpose specified.

and extending through openings in said top plate, compression springs confined between the heads of said pins and said top plate, a cam member pivotally mounted between said bars and clamping plate to force it downwardly against the tension of said springs, and a claw member carried by said cam member having its rear end turned downwardly and provided with teeth, said end passing through a suitable opening in the clamping plate, all coacting substantially as described for the purpose specified.

6. In a structure of the class described, a clamp comprising a base plate, corner posts carried by said base plate, a top plate consisting of a pair of ribbed bars secured to the corner posts and connected by cross pieces, a clamping plate disposed between said base plate and said top plate, headed pins carried by said clamping plate and extending through openings in said top plate, compression springs confined between the pins and said top plate, and a cam member pivotally mounted between said bars and disposed to engage said clamping plate to force it downwardly against the tension of said spring, all coacting substantially as described for the purpose specified.

7. In a structure of the class described, a clamp comprising a base plate, corner posts carried by said base plate, a top plate consisting of a pair of bars secured to the corner posts and connected by cross pieces, a clamping plate provided with pointed studs on its lower side disposed between said base plate and said top plate, headed pins carried by said clamping plate and extending through openings in said top plate, compression springs confined between the heads of said pins and said top plate, a cam member pivotally mounted between said bars and disposed to engage said clamping plate to force it downwardly against the tension of said springs, a claw member carried by said cam member having its rear end turned downwardly and provided with teeth, said end passing through a suitable opening in the clamping plate, a bar resting on the top of said clamping plate above said claw member and slidably on a pair of headed pins carried by said clamping plate, springs confined between the heads of said pins and said bar and normally pressing said bar into engagement with said clamping plate, a block extending transversely of the base plate and secured thereto by means of a set screw extending centrally therethrough, a bar extending transversely of the base plate behind said block and pivotally mounted on a pin centrally disposed therein, and means for adjusting said bar relative to the base plate, all coacting substantially as described for purpose specified.

8. In a structure of the class described, a clamp comprising a base plate, corner posts

carried by said base plate, a top plate consisting of a pair of bars secured to the corner posts and connected by cross pieces, a clamping plate provided with pointed studs on its lower side disposed between said base plate and said top plate, headed pins carried by said clamping plate and extending through openings in said top plate, compression springs confined between the heads of said pins and said top plate, a cam member pivotally mounted between said bars and disposed to engage said clamping plate to force it downwardly against the tension of said springs, a claw member carried by said cam member having its rear end turned downwardly and provided with teeth, said end passing through a suitable opening in the clamping plate, a bar resting on the top of said clamping plate above said claw member and slidably on a pair of headed pins carried by said clamping plate, springs confined between the heads of said pins and said bar and normally pressing said bar into engagement with said clamping plate, a bar extending transversely of the base plate and pivotally mounted on a pin centrally disposed therein, and means adjusting said bar relative to the base plate, all coacting substantially as described for the purpose specified.

9. In a structure of the class described, a clamp comprising a base plate, corner posts carried by said base plate, a top plate, a clamping plate disposed between said base plate and said top plate, headed pins carried by said clamping plate, and extending through openings in said top plate, compression springs confined between the heads of said pins and said top plate, a cam member pivotally mounted on said top plate and disposed to engage said clamping plate to force it downwardly against the tension of said springs, a block extending transversely of the base plate and secured thereto by means of a set screw extending centrally therethrough, a bar extending transversely of the base plate behind said block, and pivotally mounted on a pin centrally disposed therein, set screws carried by the rear pair of corner posts and engaging the ends of said bar for adjusting the same, ball cages provided on the bottom of said base plate and ball bearings disposed in said casting, all coacting substantially as described for the purpose specified.

10. In a structure of the class described, a clamp comprising a base plate, corner posts carried by said base plate, a top plate, a clamping plate disposed between said base plate and said top plate, headed pins carried by said clamping plate, and extending through openings in said top plate, compression springs confined between the heads of said pins and said top plate, a cam member pivotally mounted on said top plate and

disposed to engage said clamping plate to force it downwardly against the tension of said springs, a block extending transversely of the base plate and secured thereto by means of a set screw extending centrally therethrough, a bar extending transversely of the base plate behind said block, and pivotally mounted on a pin centrally disposed therein, set screws carried by the rear pair of corner posts and engaging the ends of said bar for adjusting the same, all coacting substantially as described for the purpose specified.

11. In a structure of the class described, a clamp comprising a base plate, corner posts carried by said base plate, a top plate, a clamping plate disposed between said base plate and said top plate, headed pins carried by said clamping plate, and extending through openings in said top plate, compression springs confined between the heads of said pins and said top plate, and a cam member pivotally mounted on said top plate and disposed to engage said clamping plate to force it downwardly against the tension of said springs, all coacting substantially as described for the purpose specified.

12. In a structure of the class described, a clamp comprising a base plate, corner posts carried by said base plate, a top plate consisting of a pair of bars secured to the corner posts and connected by cross pieces, a clamping plate disposed between said base plate and said top plate, headed pins carried by said clamping plate and extending through openings in said top plate, spring means supporting said clamping plate, a cam member pivotally mounted between said bars and disposed to engage said clamping plate to force it downwardly against the tension of said spring means, a claw member carried by said cam member having its rear end turned downwardly and provided with teeth, said end passing through a suitable opening in the clamping plate, a bar resting on the top of said clamping plate above said claw member and slidably supported relative to said clamping plate, and means pressing said bar into engagement with said clamping plate, all coacting substantially as described for the purpose specified.

13. In a structure of the class described, a clamp comprising a base plate, corner posts carried by said base plate, a top plate consisting of a pair of bars secured to the corner posts, and connected by cross pieces, a clamping plate disposed between said base plate and said top plate, headed pins carried by said clamping plate and extending through openings in said top plate, spring means supporting said clamping plate, a cam member pivotally mounted between said bars and disposed to engage said clamping plate to force it downwardly against the tension of said spring means, and a claw

member carried by said cam member having its rear end turned downwardly and provided with teeth, said end passing through a suitable opening in the clamping plate, all coacting substantially as described for the purpose specified.

14. In a structure of the class described, a clamp comprising a base plate, corner posts carried by said base plate, a top plate carried on said corner posts, a clamping plate disposed between said base plate and said top plate, headed pins carried by said clamping plate and extending through openings in said top plate, compression springs confined between the heads of said pins and said top plate, a fork-like cam member pivotally mounted in said top plate and disposed to engage said clamping plate to force it downwardly against the tension of said springs, a rod carried transversely of said fork-like cam member, a claw member comprising a strip having its forward end wrapped around said rod and having its rear end turned downwardly and provided with teeth, said end passing through a suitable opening in the clamping plate, a bar resting on the top of said clamping plate above said claw member and slidably on a pair of headed pins carried by said clamping plate, springs confined between the heads of said pins and said bar and normally pressing said bar into engagement with said

clamping plate, all coacting substantially as described for the purpose specified.

15. In a structure of the class described, a clamp comprising a base plate, corner posts carried by said base plate, a top plate carried on said corner posts, a clamping plate disposed between said base plate and said top plate, headed pins carried by said clamping plate and extending through openings in said top plate, compression springs confined between the heads of said pins and said top plate, a fork-like cam member pivotally mounted in said top plate and disposed to engage said clamping plate to force it downwardly against the tension of said springs, a rod carried transversely of said fork-like cam member, and a claw member comprising a strip having its forward end wrapped around said rod and having its rear end turned downwardly and provided with teeth, said end passing through a suitable opening in the clamping plate, all coacting substantially as described for the purpose specified.

In witness whereof I have hereunto set my hand and seal in the presence of two witnesses.

JOHN C. DUNTON. [L.S.]
